UNITED STATES PATENT OFFICE.

WILLIAM H. EBLEN, OF WINDROCK, TENNESSEE.

OBSTETRICAL APPLIANCE.

1,031,841.

Specification of Letters Patent.

Patented July 9, 1912.

Application filed September 6, 1911. Serial No. 647,996.

To all whom it may concern:

Be it known that I, WILLIAM H. EBLEN, a citizen of the United States, residing at Windrock, in the county of Anderson and State of Tennessee, have invented a new and useful Improvement in Obstetrical Appliances, of which the following is a specification, reference being had to the accompanying drawing.

10 My improvement relates to apparatus intended to aid the patient during accouche-
ment.

The apparatus comprises foot-rests and knee-rests and hand holds for the use of the patient in exerting muscular strain.

15 In the accompanying drawings, Figure 1 is a plan of an apparatus embodying my improvement; Fig. 2 is an end elevation of the same apparatus; Fig. 3 is a section on the line 3—3, of Fig. 1; Fig. 4 is a section on the line, 4—4, of Fig. 2; Fig. 5 is a section on the line, 5—5, of Fig. 2; Fig. 6 is a section on the line, 6—6, of Fig. 2; Fig. 7 is a section on the line, 7—7, of Fig. 1; Fig. 8 is a section on the line, 8—8, of Fig. 1.

20 Referring to said drawings, A, A, are base bars forming two opposite sides of a quadrilateral horizontal frame. B, is a foot-
rest bar extending from the rear end of
30 one of the base bars through the rear end of the other base bar and forming the rear side of said quadrilateral frame. C, is a front connecting bar joining the front ends of the bars, A, and forming the front side
35 of said quadrilateral frame.

From the rear end of each base bar, A, rises an oblique member, D, the upper end of which is joined to a similar front oblique member, E, rising from the front end
40 of the adjacent base bar. From the meet-
ing upper ends of one pair of oblique mem-
bers, D and E, a knee-rest bar, F, extends
45 to the upper meeting ends of the other pair
of oblique members, D and E. Thus said
knee-rest bar is supported above and for-
ward of the foot-rest bar, according to the
height and inclination of said oblique mem-
bers. To each of the oblique members, E, is
50 secured a hand hold, G, as will be herein-
after described. The foot-rest bar and the
knee-rest bar are preferably made rotatable,
in order that the foot-rests and the knee-
rests borne, respectively, by said bars may
automatically tilt in response to the pres-

sure of the foot and the knee in order to 55
make the most extended engagement be-
tween said rests and the feet and knees.
Provision is also made for adjusting the
height of the knee-rest bar and its distance
forward of the foot-rest bar; and portions 60
of the apparatus are made detachable or
foldable, or both, in order that the appa-
ratus may be put into compact form when not
in use. And the foot-rests are made adjust-
able lengthwise upon the foot-rest bar; and 65
the knee-rests are similarly made adjustable
on the knee-rest bar and removable there-
from, as will be hereinafter described.

In the form shown in the drawings, the 70
foot-rest bar is four-sided in cross section
and has at its middle a carriage-brace joint,
B¹. At each end said bar has a round neck,
B², with a head, B³. Said neck rests in a
hook, A¹, formed on the end of the base bar,
A, said hook opening upward and toward 75
the opposite end of said bar. Said hook
forms a bearing for the neck, B². The foot-
rest bar may be removed from said hooks
when the openings of the latter are unob-
structed. But when said apparatus is set 80
up for use, a sleeve, D¹, surrounding and
slidable upon each base bar, A, rests across
the opening of the adjacent hook, as shown
in the lower left hand portion of Fig. 2.
Thus the necks or journals, B², of the bar, 85
B, are temporarily confined in the bearings
formed by said hooks. Each such sleeve is
secured to its bar, A, by means of a thumb
set screw D².

B⁴ are the foot-rests. These may be of 90
any convenient size adapted for engagement
by the feet of the patient. On the bottom of
each such rest is a sleeve, B⁵, fitting slidably
upon the four-sided bar, B. A set screw,
B⁶, extends through said sleeve and bears 95
upon said bar for binding the foot-rest
firmly upon said bar. When said screw is
loose, the foot-rest may be shifted along
the length of said bar and, if desired, re-
moved from the latter, the heads, B³, being 100
no larger than the interior of said sleeve.

Each oblique member, D, is composed of
a bar or rod, D³, and a tube, D⁴, into which
said bar or rod extends slidably. The upper
end of said tube has a slot, D⁵; and said 105
end is surrounded by a strap clamp, D⁶,
through the ends of which extends a thumb
screw, D⁷. By tightening said screw, said

clamp compresses the upper end of said tube sufficiently to cause the binding of said tube upon the bar, D³, so as to prevent movement of said bar in said tube. At its lower end, 5 each oblique member, D, is hinged to the sleeve, D¹, by a hinge, D⁸, having an axis parallel to the bar, B.

The front connecting bar, C, has in its middle a carriage-brace joint, C¹; and at 10 each end said bar is connected to the adjacent base bar, A, by means of a hinge, C², having an upright axis.

The front end of each of the base bars, A, is surrounded by a sleeve, E¹, slideable on 15 said bar. A set screw, E², extends through one side of each such sleeve for binding the latter to its bar, A.

Each oblique member, E, is composed of a bar or rod, E³, and tube, E⁴, into which 20 said rod extends slidably. The upper end of said tube has a slot, E⁵; and a strap clamp, E⁶, extends around the upper end of the tube, and a thumb screw, E⁷, extends transversely through the ends of said clamp.

25 By tightening said screw, said clamp is made to bind upon said tube sufficiently to compress the latter for binding upon said bar to prevent movement of the latter in the tube. The lower end of each member, E, is joined to the sleeve, E¹, by a hinge, E⁸, which is horizontal and parallel to the bar, C. The upper ends of the oblique member, D, and E, are secured to each other by a knuckle joint the upper end of one of said 30 members being slotted vertically to receive the upright flattened end of the other of said members. In the drawings the member, D, is slotted. At the point of such over-lapping, each member, D, has horizontal 35 bearings, D⁹, while the members, E, have similar bearings, E¹⁰, in line with the bearings, D⁹. At each end, the knee-rest bar, F, has a journal, F¹, extending through the bearings, D⁹ and E¹⁰. To hold said journals in said bearings, a latch, F², is hinged to each end of said bar at, F³, in proper position to adapt it to lie flatwise upon said bar and the upper ends of the members, D and E, and have a head, F⁴, extend down- 40 ward over the outer face of the adjacent member, D. At its middle, the knee-rest bar has a carriage-brace joint, F⁵. F⁶, F⁷, are knee rests supported by the knee-rest bar, each knee-rest having a sleeve, F⁸, slide- 45 able upon said bar, and a set-screw, F⁹, extending through said sleeve to bear against said bar and bind said sleeve immovably to said bar. After loosening said set-screw, said knee-rest may be moved along the 50 length of said bar.

On each bar or rod, E³, is a strap ring, G; and on each such ring is a strap, G¹, leading to and connected with a hand hold, G². Said straps may be of any desired length. 55 Said ring has an eye, G³, through which the

rod or bar, E³, extends. The ring may be loose on said bar so that the ring may slide downward and rest upon the clamp, E⁶.

As already pointed out, the foot-rests, B⁴, are adjustable along the length of the bar, 70 B; and it is to be noted that said bar may turn on the journals, B², to allow the foot-rests to rock to conform to the sole of the foot of the patient. It has also been indicated that the knee-rests are adjustable along the 75 length of the bar, F, and it is to be observed that the journals, F¹, allow said bar to rock or turn sufficiently to permit the knee-rests to adapt themselves to the surface of the knee of the patient bearing against them. 80

The distance between the foot-rests and the knee-rests is varied by loosening the clamps, D⁶, and moving the rods, D³, up or down and then again tightening said clamps. During such movement, the oblique members, E, turn on their hinges, E⁸. If it is desired to change the inclination of the plane cutting the foot-rests and the knee-rests, the members, E, are shortened or lengthened by releasing the clamps, E⁶, and moving the rods, E³, up or down in the tubes, E⁴, thus moving the knee-rests in an arc having its axis near the foot-rest bar. 85

In operation, the patient has six points of engagement with the apparatus or appliance. The legs being partially folded, the feet rest upon the foot-rests, B⁴, the knees bear rearward against the knee-rests, F⁶, and the hands grip the hand holds, G². And those six points are used as points of resistance and the exertion of muscular strain. Strain applied to the hand holds is resisted by the feet and the knees; and conversely, the strain applied to the foot-rests between the feet and the knee-rests by the knees is 100 resisted by the hands.

For folding and packing the apparatus for storage or convenient carrying when not in use, the latches, F², are raised and the oblique members, D and E, sprung sufficiently 110 to free the journals, F¹, from the bearings, D⁹ and E¹⁰, thus freeing the said bar from the structure. Then said bar may be folded on its joint, F⁵, whereby said bar is reduced to one half its former length. The removal 115 of said bar releases the upper ends of the oblique members, D and E, from each other. The bars, D³ and E³, may be moved downward in their respective tubes and said members folded downward against the adjacent bars, A, A. The bars, D³ and E³, may be taken out of their tubes, if so desired. By moving the clamps, D¹, forward, the journals, B², may be moved out of the 120 hook bearings, A¹. And the foot-rests may be removed from said bar, B, and said bar then folded upon the joint, B¹. The connecting bar, C, may then be folded upon the joint, C¹, whereby the two sections of said bar are folded against the adjacent base 125 130

bars, A, upon the hinges, C², whereby the base bars, A, A, are brought close to each other. The straps, G¹, being flexible, they and the hand holds may be folded closely to the other parts. If so desired, the strap rings, straps, and hand holds, may be detached by drawing the rods, E³, out of the eyes, G³, of the rings. 5

The several parts should be made of strong metal and should be designed for the combination of minimum weight and maximum strength. Regarding dimensions, it may be noted that in an apparatus which I have constructed and used, the foot-rest bar and the front connecting bar are twenty-one inches long while the base bars are sixteen inches long, the oblique members, D and E, being set relatively approximately as shown in Fig. 2. 15

I claim as my invention:

1. In an apparatus of the nature described, the combination of foot-rests, knee-rests, and hand holds, and relatively rigid supports for the foot-rests and the knee-rests, substantially as described. 20

2. In an apparatus of the nature described, the combination of foot-rests, knee-rests, and hand holds, the foot-rests and the knee-rests being rigidly supported and the knee-rests being adjustable relative to the foot-rests, substantially as described. 25

3. In an apparatus of the nature described, the combination of foot-rests, knee-rests, and hand holds, the foot-rests and the knee-rests being rigidly supported and the knee-rests being adjustable with reference to each other and to the foot-rests, substantially as described. 35

4. In an apparatus of the nature described, the combination of foot-rests, knee-rests, and hand holds, the foot-rests and the knee-rests being rigidly supported and the foot-rests being adjustable toward and from each other, substantially as described. 40

45 5. In an apparatus of the nature described, the combination of foot-rests, knee-rests, and hand holds, the foot-rests and the knee-rests being rigidly supported and the foot-rests being adjustable toward and from each other and the knee-rests being adjustable toward and from each other, substantially as described.

55 6. In an apparatus of the nature described, the combination of rocking foot-rests, knee-rests, and hand holds, and relatively rigid supports for the foot-rests and knee-rests, substantially as described.

60 7. In an apparatus of the nature described, the combination of foot-rests, a rocking support therefor, knee-rests and a rigid support therefor which is adjustable relative to the foot-rest support, and hand holds, substantially as described.

65 8. In an apparatus of the nature described, the combination of a rocking foot-

rest support, foot-rests on said support, a rigid knee-rest support adjustable relative to said foot-rest support, knee-rests seated on the knee-rest support adjustable toward and from each other, and hand holds, substantially as described. 70

9. In an apparatus of the nature described, the combination of a rocking foot-rest support, foot-rests seated on said support adjustable toward and from each other, a rigid knee-rest support adjustable relative to said foot-rest support, knee-rests on the knee-rest support, and hand holds, substantially as described. 75

10. In an apparatus of the nature described, the combination of a rocking foot-rest support, foot-rests seated on said support adjustable toward and from each other, a rigid knee-rest support, knee-rests seated on said support adjustable toward and from each other, and hand holds, substantially as described. 80

11. In an apparatus of the nature described, the combination of a rocking foot-rest support, foot-rests seated on said support, a rigid rocking knee-rest support, knee-rests on said support, and hand holds, substantially as described. 85

12. In an apparatus of the nature described, the combination of foot-rests, knee-rests, and hand holds, and relatively fixed supports for the foot-rests and the knee-rests, the support for the knee-rests being adjustable in an arc having its axis adjacent the foot-rest support, substantially as described. 90

13. In an apparatus of the nature described, the combination of a foot-rest support, foot-rests on said support, oblique members meeting at their upper ends, a knee-rest support supported by said oblique members, knee-rests on said knee-rest support, and hand holds, substantially as described. 100

14. In an apparatus of the nature described, the combination of a foot-rest support, foot-rests on said support, oblique members meeting at their upper ends, a rotatable knee-rest support supported by said oblique members, knee-rests on said knee-rest support, and hand holds, substantially as described. 110

15. In an apparatus of the nature described, the combination of a rotatable foot-rest support, foot-rests on said support, a knee-rest bar, knee-rests on said bar, relatively fixed supports for said bar, and hand holds, substantially as described. 120

16. In an apparatus of the nature described, the combination of a frame comprising front, rear, and end members and oblique members rising from the end members and meeting at their upper ends, and a knee-rest member extending from the meeting ends of one pair of the oblique mem- 125

bers to the meeting ends of the other oblique members, knee-rests on said knee-rest member, foot-rests supported by said rear frame member, and hand holds secured to said frame, substantially as described.

17. In an apparatus of the nature described, the combination of a frame comprising front, rear, and end members and adjustable oblique members rising from the 10 end members and meeting at their upper ends, and a knee-rest member extending from the meeting ends of one pair of adjustable oblique members to the meeting ends of the other oblique members, knee-rests on said knee-rest member, foot-rests supported by said rear frame member, and hand holds secured to said frame, substantially as described.

18. In an apparatus of the nature described, the combination of base bars having bearings at their rear ends, a foot-rest bar journaled removably in said bearings, foot-rests on said bar, a knee-rest bar, means for detachably supporting said bar above 25 said base bars, knee-rests on said knee-rest bar, and hand holds, substantially as described.

19. In an apparatus of the nature described, the combination of a base frame, two oblique members rising at each end of the frame and meeting at their upper ends, a knee-rest member having a journal and latch mechanism at each end for engaging the meeting ends of said oblique members, knee-rests on said knee-rest bar, and hand holds, substantially as described.

20. In an apparatus of the nature described, the combination of framing comprising two base bars having hooks constituting bearings, a foot-rest bar resting in 40 said hooks, an adjustable sleeve surrounding each base bar adjacent the hook of said bar for retaining said foot-rest bar in said bearings, foot-rests on said foot-rest bar, knee rests, and hand holds, substantially 45 as described.

In testimony whereof I have signed my name, in presence of two witnesses, this 29th day of August, in the year one thousand nine hundred and eleven.

WILLIAM H. EBLEN.
